UNITED STATES PATENT OFFICE.

CHARLES H. USHER, OF CHICOOEE FALLS, MASSACHUSETTS, ASSIGNOR TO LAMB
KNITTING MACHINE COMPANY, A CORPORATION OF MASSACHUSETTS.

SAFETY STOP.

Application filed March 28, 1924. Serial No. 702,684.

This invention relates to a stop device for machines generally. Its object is to provide an improved unitary stop device for attachment to almost any machine having a belt or clutch shifting rod operable to control a clutch or belt to start and stop the machine. By supplying a spring operable to shift said rod when the latter is released by the operation of the latch of my device the machine 10 may be stopped.

The broad idea of releasing a spring pressed rod to shift a clutch or belt is very old. My improvement is in the particular mechanism I provide for the purpose.

15 I preferably use an electrically operated door lock of standard construction which may be bought in hardware stores. This I combine in a frame with a simple lever pivoted in the frame. The lock acts as a latch 20 on the lever and the lever is adapted to act as a latch on the spring pressed rod of the machine. The said frame is arranged to position the lever with respect to the rod whereby the lever may work on the rod.

25 The frame with the lock and lever wholly supported therein constitutes a unit for convenient attachment to any machine. The specific structure herein disclosed has been applied to a knitting machine.

30 The structure constituting my invention is shown in the drawings, in which:

Fig. 1 is a side elevational view of the device; and

Fig. 2 is a view taken on the line 2—2 35 of Fig. 1.

The invention will now be described in detail. A frame 1 is provided, preferably of sheet metal formed into the shape of a U having parallel side walls 2 connected by an upper end wall 3. A standard electric door lock L interfits the side walls 2 of the frame and is secured thereto by suitable means such as rivets or screws 4. The door lock may be of any standard construction but a form 40 that I have found to be adapted for use in connection with my invention will now be described. A latch 5 is pivoted to the lock frame at 6 and carries in its outer end a roller 7. A spring (not shown) is provided 45 within the lock to urge the latch toward its outer or latched position shown in Fig. 1. A keeper 8 movable in the lock is constructed and arranged to lie behind the latch to hold the same in its latched position, to prevent an accidental depressing or non-latch-

ing movement thereof. Magnets 9 within the lock are provided to actuate the plate or keeper 8 and withdraw the same from engagement with the latch mechanism whereby the latch is permitted to be depressed, 60 as will later appear. It will be understood that the latch is normally spring pressed outwardly to a latched position and held therein by a keeper and that the magnets are employed to withdraw the latch keeper, to permit the latch to be depressed by any pressing action that may be applied to the roller of the latch. The operating details of the latch device 5 are all well known and may be found in standard electric door lock constructions as sold in most hardware stores. 70

A lever member 10 which functions as a lock upon the shifter rod R is pivoted to the frame at 11 and is provided with a latch engaging notch 12 and a circular latch depressing surface 13 best shown in Fig. 1. The lever 10 is adapted to be swung by the rod R in a counter-clockwise direction from its rod latching position, shown in Fig. 1, to non-latching positions, as will later be 80 described.

A reciprocating rod R is shown that may represent a belt or clutch shifting rod of any machine and that may be guided in a guideway 14 fixed to a frame 15 or other 85 part of the machine.

A collar 16 is fixed to the rod R and a coil spring 17 is interposed between the collar and bearing guideway 14 that tends to move the rod to the left and hold the belt or clutch 90 shifter in a non-operating position when released by the stop device.

In connection with the embodiment of the invention shown, it will be assumed that the rod is moved to the right against the action 95 of the spring 17 to operate a clutch or belt shifter for operating the machine while a reverse movement to the left will disengage the driving mechanism to stop the machine. A collar 18 fixed to the rod R is provided 100 with a disk or flange 19 that is adapted to engage a notch 20 provided in the upper side of the lever 10.

The frame 1 of the stop device may be conveniently secured to the frame 15 of a machine by screws 21 or the like and is so located with respect to the rod R that the collar 19 thereof may engage with the notch 20 of the lever 10.

To operate a machine with which my 110

stop device is used, the rod R is moved by hand to the right and against the action of the spring 17 for engaging the clutch or other driving mechanism. The collar 19 of the 5 rod automatically engages the notch 20 of the lever 10 and moves the lever in a clockwise direction to the position shown in Fig. 1. The spring pressed latch 5 moves to a latching position wherein the roll 7 is in 10 engagement with the notch 12 of the lever and holds the lever from a counter-clockwise movement. The operation of shifting the rod R therefore sets the latch device as the latch 5 and its roll 7 engages notch 12. 15 The rod being urged to its non-operating position by the spring 17 is held in an operating position by means of the collar 19, lever 10 and latch 5. By the arrangement shown, the thrust of the spring 17 upon 20 the latch 5 is greatly reduced by reason of the ratio of the leverages between 11 and 20 and between 11 and 12. This reduction enables me to use my simple electrical latch device even though the spring 17 is very 25 powerful. The arrangement constitutes one feature of my invention.

Magnets 9 of the lock L are preferably 30 connected by suitable means to any circuit that may include one or more dry cells and a circuit controlling switch. The circuit switch may take any form such as a push button or other device adapted to open or close the circuit but is usually attached to or controlled by relatively movable parts of 35 the machine itself. That is, the circuit control may be so arranged that the circuit may be closed by the machine at the termination of any number of cycles or at any other time depending upon the type of machine with which the device is used.

Whenever the circuit is closed and the 40 magnets supplied with an electrical current, the keeper 8 is elevated to permit a depressing movement of the latch. Since the lever 10 is at all times being urged in a counter-clockwise direction by its connection with the spring pressed rod R the withdrawal of the keeper permits the lever to move to the right and to depress the 45 latch 5. As the lever 10 swings to the right the roll of the latch is engaged by the cam surface 13 of the lever which holds the latch in its depressed position. As the lever swings to the right the collar 19 of the rod is released by the notch 20 and the 50 spring 17 actuates the rod R to the left and disengages the clutch or pulley driving mechanism controlled thereby. When it is desired to again operate the machine by a 55 right hand movement of the rod the lever and latch are reset to the latching position shown in Fig. 1 by the engagement of the collar 19 and notch 20 of the lever which moves frame 10 to the position shown in 60 Fig. 1.

From the foregoing description, it is seen that no matter how powerful the rod shifting spring is, the leverage between the latch of the lock and the latch of the simple lever on the rod is such that almost no power at 70 all will release the lever on the rod. In actual practice, a single dry cell will operate the lock to release the lever arm even against a very powerful spring.

I consider that the chief feature of my 75 invention is the extreme simplicity of the means by which I supply an effective electrically operated stop device to machines of all sorts, even though they require a very powerful spring to shift the starting rod. 80

What I claim is:

1. The combination of a spring pressed shifter rod with a release device comprising, a frame, a collar carried by said rod, a lever pivoted in said frame having a latch notch and a recess for engagement with said collar, a lock carried in said frame including an electrically operated latch for engaging the notch of said lever, all adapted and arranged whereby the rod is held from a shifting movement by the lever while the said lever is held in latched position by the latch of the lock. 85

2. A unitary stop device for application to machines having spring pressed shifting rods, said device comprising a U shaped frame adapted to be attached to the machine so its legs straddle the shifting rod, a curved lever pivoted to the frame close by the shifting rod, an electrically operated latch mechanism or lock mounted between the legs of the frame with its latch located at a remote point from said pivot, said lever being provided with releasable means to engage and hold the rod adjacent said pivot and means engageable with said latch remote from said pivot, the surfaces of said curved lever being designed to cooperate with the rod and latch to automatically set the stop device from the movement of the rod in one direction and to hold the latch out of operation upon the movement of the rod in the opposite direction. 95

3. A unitary stop device comprising a U shaped frame having an electrically operated door lock mounted between its legs with the latch thereof positioned at the outer openings between the legs of the frame, a lever pivoted in the frame above the lock at a point remote from the latch thereof but spaced from the cross piece of the frame, said lever having legs surrounding the said lock and having means engageable with latch thereof and also having additional latch means adjacent its pivot to engage a shifting rod passing through the frame above the pivot. 110

In testimony whereof I have affixed my signature.

CHARLES H. USHER.
